(57) **CLAIM**

The ornamental design for a hormone tester, as shown and described.

DESCRIPTION

FIG. 1 is a front view of a hormone tester showing my new design;

FIG. 2 is a rear view of the hormone tester;

FIG. 3 is a left side view of the hormone tester, a right side view being a mirror image thereof;

FIG. 4 is a top view of the hormone tester;

FIG. 5 is a bottom view of the hormone tester; and,

FIG. 6 is a top front side perspective view of the hormone tester.

The well formed in the front face of the tester, as shown in FIG. 6, has a consistent depth relative to the front face.
